UNITED STATES PATENT OFFICE.

BYRON SYLVEUS HOVEY AND WALTER H. DRAKE, OF STOCKVILLE,
NEBRASKA.

CHURN.

SPECIFICATION forming part of Letters Patent No. 425,429, dated April 15, 1890.

Application filed October 9, 1889. Serial No. 326,453. (No model.)

To all whom it may concern:

Be it known that we, BYRON SYLVEUS HOVEY and WALTER H. DRAKE, citizens of the United States, residing at Stockville, in the county of Frontier and State of Nebraska, have invented a new and useful Churn, of which the following is a specification.

This invention has relation to that class of churns known as "body-working," and among the objects in view are to provide a churn-support constructed and adapted to receive an ordinary crock or other similar vessel usually contained in all households.

The invention consists in certain features of construction, which will hereinafter appear, together with numerous other objects.

Referring to the drawings, Figure 1 is a perspective of a churn-support constructed in accordance with our invention. Fig. 2 is a detail in perspective of the churn-body-embracing frame, and Fig. 3 a similar view of the locking-cover. Fig. 4 is a vertical longitudinal section of the complete churn on the line $\alpha\alpha$ of Fig. 1.

Like numerals of reference indicate like parts in all the figures of the drawings.

1 represents a suitable base, from each end of which there projects vertical standards 2, having bearings 3 formed near their upper extremities.

4 represents the churn-body-receiving frame, and the same consists, in this instance, of a metal strap adapted to encircle the body of the churn at about its middle, and is provided with opposite bearing-studs 5, adapted to be removably mounted in the bearings 3, one of said studs being continued outside of its bearing and there provided with an operating-crank 6. The upper edge of the strap is provided with, in this instance, four upwardly-projecting arms 7 and with a similar number of downwardly-projecting arms 8, the downwardly-projecting arms having their ends inwardly bent at a right angle, as at 9, to form a bottom support for the churn-body.

10 represents the churn-body, which may be either a specially-constructed body, or, as before stated, any suitable domestic vessel, and preferably an ordinary crock. The crock is placed in position so that its bottom rests

upon the inwardly-turned ends 9, and the upper end of the crock is provided with a circular cover 11, between which and the crock is located a suitable packing-ring 12. In each pair of upwardly-projecting arms 55 there is formed a bearing opening or perforation 13, and in the four arms there is pivotally mounted a pair of opposite swinging bails 14, adapted to be swung down upon the cover for the purpose of holding the same 60 snugly upon the crock. The cover is provided at its center with an upwardly-projecting perforated lug 15, upon which is pivoted a cam-lever 16, bifurcated at its cam end to receive the lug, and through the lever and 65 lug is inserted a pivot 17. The periphery of each of the cams is grooved, as at 18, and the manner of operating the cam is as follows: The cream is placed in the crock and the crock seated in the frame 4, after which the 7c cover is placed in position, the bails swung into place upon the cover, and the cam-lever lowered so that each of its cam-faces bind upon a bail. The churn may now be operated in the usual manner.

If desired, we may provide the crock with a loose dasher 19, consisting of a square cube adapted to be thrown from end to end of the churn by the tumbling of the same, the angles of the cube serving as cutters for the cream. 80

Having thus described our invention, what we claim is—

1. The combination, with opposite standards, of a churn-body support pivotally mounted therein and comprising upper and lower 85 projecting arms and a central ring, the lower arms terminating in churn-body supports, and the upper arms being provided with churn-body-retaining bails, a churn-body mounted in the support, a cover mounted over 90 the body, the bails mounted over the cover, and a cam-lever pivoted upon the cover and adapted to lock the bails, substantially as specified.

2. The combination, with the standards, of 95 the churn-support pivotally mounted therein and comprising the body-embracing ring, the lower inwardly-turned churn-supporting arms and the upwardly-projecting embrac-ing-arms, the churn mounted in the ring, the 100

cover mounted on the churn, the pivoted bails mounted in the upwardly-projecting arms and taking over the cover, the perforated lug mounted upon the cover, and the cam-lever bifurcated to embrace the lug and pivoted thereto and having its cam-faces provided with grooves, and each adapted to impinge upon a bail, substantially as specified.

3. The combination, with a base having 10 opposite standards provided at their upper ends with bearings, of the herein-described churn-support, formed of sheet metal and consisting of a central ring having opposite bearing-studs mounted in the bearings, and 15 upper and lower projecting arms, the former being provided with devices adapted to interlock with locking devices upon a churn-cover for retaining the churn within the sup-

port and the latter inwardly bent at their lower ends and adapted to support a churn- 20 body, substantially as specified.

4. The churn-body, the skeleton support therefor, the bails pivoted in the support, the churn cover or lid having the cam-lever with the grooved cam-faces, the central portion of 25 each bail being engaged in the grooved faces of the cam-lever, as set forth.

In testimony that we claim the foregoing as our own we have hereto affixed our signatures in presence of two witnesses.

BYRON SYLVEUS HOVEY.
WALTER H. DRAKE.
